VICTOR H. JENNINGS, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

SHEATH OR SCABBARD.

1,133,144.

Specification of Letters Patent. Patented Mar. 23, 1915.

Application filed April 27, 1912. Serial No. 693,667.

To all whom it may concern:

Be it known that I, VICTOR H. JENNINGS, a citizen of the United States, residing at Worcester, in the county of Worcester, State 5 of Massachusetts, have invented a certain new and useful Improvement in Sheaths or Scabbards, of which the following is a specification, reference being had therein to the accompanying drawings.

10 The invention relates to sheaths or scabbards, such, for instance, as those which are employed for knives, bayonets, bolos, and various other weapons and implements.

15 It consists in a sheath or scabbard having a tubular fabric-covering of novel character hereinafter described and claimed.

An embodiment of the invention is shown in the drawings, in which latter,—

Figure 1 is a rear elevation of a sheath or 20 scabbard for a sword-bayonet having the said embodiment of the invention applied thereto. Fig. 2 is a top view of the upper end of the said sheath or scabbard. Fig. 3 is a rear elevation thereof, with the wire 25 hanger and the cloth hanger or tab both omitted, and portions of the fabric-covering broken away. Fig. 4 is an elevation of the upper portion of the tubular fabric-covering of Figs. 1 and 3, before being applied to the 30 body and mouth-piece of the sheath or scabbard. Fig. 5 is a top view of the said tubular fabric-covering. Fig. 6 is an elevation of the portion of fabric-covering that is represented in Fig. 4, but before being expanded, 35 folded-in and stitched as in Fig. 4. Fig. 7 is a top view of the said portion as shown in Fig. 6.

Having reference to the drawings,—the sheath or scabbard shown therein is of the 40 customary flattened shape in cross-section and comprises the body 1, shown in Fig. 3 by breaking away a portion of the cover, the cap or mouth-piece 2, the cover 3, the cloth hanger or tab 4, the wire hanger 5, and the 45 leather covering 6 for the lower end of the sheath or scabbard. The body 1 is of usual character and construction, as for instance wood covered with rawhide. The cap or mouth-piece 2 upon the upper end of the 50 body 1 is made of metal or other suitable material, and is formed with the entrance-slot, 2^a, Fig. 2, in line with the blade-receiving space within the body 1. This cap or mouth-piece surrounds and incloses the up-

per end-portion of the body 1, forming an 55 enlargement at the upper end of the sheath or scabbard.

In usual practice heretofore the material employed as the covering of a sheath or scabbard has been cut to pattern from a flat 60 sheet of leather or cloth, then folded so as to bring its longitudinal margins together at one edge of the covering, and stitched through and through such margins, forming 65 a longitudinal seam which unites the folded-in margins together and thereby closes the cover lengthwise in the form of a tube. Having been thus formed into a tube, the cover has been drawn upon the body and up over the exterior of the cap or mouth-piece. The pattern has been proportioned 70 properly to cause the upper portion of the cover to fit the enlargement of the cap or mouth-piece, and to cause the remaining portion of the cover to fit the body below 75 such enlargement. This method of making a cover is open to the very grave objection that it produces a prominent projecting fin or ridge along one edge of the sheath or scabbard, extending from the upper end of 80 the latter to the lower end thereof, where the margins of the material have been stitched together. This is especially true in the case of a cover made of woven material, which requires to have its cut edges folded 85 or turned back inward as described in order to conceal and protect the raw edges. The said fin or ridge is unsightly and mars the appearance of the covered sheath or scabbard, and the work of making a properly 90 fitting covering and applying the latter is difficult. The stitched seam sometimes rips as a result of the breaking of stitches due to improper formation of stitches or weakness of the thread employed therein, or to decay 95 and weakening of the thread, or as a result of injury to the stitches due to wear or hard usage.

My invention eliminates the protruding fin or ridge aforesaid, and the exposed seam 100 extending the length of the sheath or scabbard, and provides a substantially seamless cover of novel character.

In accordance with the invention I make the cover 3 of a fabric of firm and inextensible weave, woven in seamless tubular form throughout the entire length of the portion thereof which fits the body 1, and pro-

portioned in diameter to fit snugly and smoothly upon the exterior of the said body. As produced in the loom the tube is flattened as indicated in Fig. 6. The portion of the fabric which fits the exterior of the cap or mouth-piece 2 is woven in folded form as in Fig. 7, in continuation of the flattened tube, but with a longitudinal slit in one flat side, and with a widening 3^a, Fig. 7, upon the portion of the fabric at one side of the slit which laps past the margin 3^b of the fabric at the other side of the slit, as shown in Fig. 7, and as indicated by dotted lines in Fig. 6. This longitudinal slit permits lateral spreading of the upper end of the fabric, as illustrated in Fig. 4, to fit the exterior of the cap or mouth-piece, producing a flaring mouth-portion as in Fig. 4. The widening 3^a is made of width sufficient to provide two overlapping plies which will permit the required extent of expansion of the said mouth-portion without exposing an opening between the edges at opposite sides of the slit. The two overlapping plies are secured together by a line of stitches 7, Fig. 4, thereby fixing the mouth-portion in its flaring form. As both edges at the slit are firm selvaged edges, produced in the usual manner of forming selvages, there are no loose ends of threads along the slit, and there is no tendency to raveling at the slit.

The fabric is woven in a continuous web in which a length of tubular fabric is succeeded by a slitted mouth-portion, that by a second length of tubular fabric, that by a slitted mouth-portion, and so on, the said web being divided up into cover-lengths by severing it transversely at the upper end of each slitted mouth-portion. The raw cut end of the latter is concealed and protected by folding the same inward into the upper end of the cover, as represented in Fig. 3. In doing so, the margin at 3^b, Fig. 7, is turned inward over and around the turned-down upper end of the widening 3^a, thereby inclosing the free margin of said widening as in Fig. 5. The folding-over provides a smooth, solid, and firm continuously-closed mouth-end, as shown in Fig. 3. The folded-in portion or hem is secured by lines 8, 8, of stitches extending around the mouth-end of the cover and engaging with all the contacting thicknesses. The cap or mouth-piece, 2, is formed with a radial flange 2^b against which the said smooth, solid and firm mouth-end of the cover fits snugly, as in Fig. 3.

The cloth hanger or tab 4, Fig. 1, is applied to the broad or flat side of the cover which contains the longitudinal slit, being fitted over the slit and the line of stitches 7, and is secured to the said side of the cover by lines of stitches 9, 9, etc. Thereby the slit and the line of stitches 6 are concealed and protected. The length of the

longitudinal slit that is woven in the mouth-portion of the cover, and its selvaged edges, and the width of the widening, as well as the mode of weaving, may vary in practice. The overlapping single-ply selvaged portions 3^a, 3^b, at the slit provide for the expansion of the mouth-portion of the cover, and for completely closing such portion, without bunchiness due to excess of material. The cover may be caused to adhere to the surface of body 1 by means of glue or other cementitious substance. The widening at 3^a is produced by interweaving the weft or filling with supplemental warp-threads (not shown) which are floated from one widening to the next and subsequently cut away, although they may be interwoven in the tubular portion of the fabric between widenings if desired.

I claim as my invention:

1. The combination with a sheath or scabbard having an exteriorly-enlarged mouth-end, of a fabric-covering of seamless tubular weave fitting the said body, having a mouth-portion formed with a longitudinal slit, with both margins at such slit woven selvaged and also woven overlapped with each other, and having their overlapping portions partly expanded to suit the enlarged mouth-end and permanently secured together.

2. The combination with a sheath or scabbard having an exteriorly-enlarged mouth-end, of a fabric-covering of seamless tubular weave fitting the said body, having a mouth-portion expanded to fit said exteriorly-enlarged mouth-end, formed with a longitudinal slit and integral widening, with both margins at such slit woven selvaged, and also woven overlapped with each other, and having their overlapping portions partly expanded and permanently secured together.

3. The combination with a sheath or scabbard having an exteriorly-enlarged mouth-end, of a fabric-covering of seamless tubular weave fitting the said body, having a mouth-portion expanded to fit said exteriorly-enlarged mouth-end, formed with a longitudinal slit and integral widening, with both margins at such slit woven selvaged and also woven, overlapped with each other, and having their overlapping portions partly expanded and permanently secured together, and a suspending tab covering and protecting the slit, widening, and securing means.

4. The combination with a sheath or scabbard having an exteriorly-enlarged mouth-end, of a fabric-covering of seamless tubular weave fitting the said body, having a mouth-portion expanded to fit said exteriorly-enlarged mouth-end, formed with a longitudinal slit and integral widening, with both margins at such slit woven sel-

vaged and also woven, overlapped with each other, and having their overlapping portions partly expanded and permanently secured together, and with the end of such 5 mouth-portion turned in upon itself and one overlapping portion inclosing and confining the other, producing a firm and continuously-closed mouth-end.

5. The combination with a sheath or scabbard having an exteriorly-enlarged mouth-end, of a fabric-covering of seamless tubular weave fitting the said body, having a mouth-portion expanded to fit said exteriorly-enlarged mouth-end, formed with a 10 longitudinal slit and integral widening, 15 with both margins at such slit woven sel-

vaged and also woven, overlapped with each other, and having their overlapping portions partly expanded and permanently secured together, and with the end of such 20 mouth-portion turned in upon itself and one overlapping portion inclosing and confining the other, producing a firm and continuously-closed mouth-end, and a suspending tab covering and protecting the slit, 25 widening, and securing means.

In testimony whereof I affix my signature in presence of two witnesses.

VICTOR H. JENNINGS.
